Primary Examiner — Philip S Hyder*Assistant Examiner* — Roselynne Cody(74) *Attorney, Agent, or Firm* — McDonald Hopkins LLC(57) **CLAIM**

The ornamental design for a handle for a ratchet assembly, as shown and described.

DESCRIPTION

FIG. 1 is a top perspective view of a handle for a ratchet assembly showing our new design;

FIG. 2 is a side view thereof;

FIG. 3 is a top view thereof;

FIG. 4 is a bottom view thereof;

FIG. 5 is a front view thereof; and,

FIG. 6 is a rear view thereof.

The broken lines in the figures are included for the purpose of illustrating portions of a ratchet assembly and a handle for the ratchet assembly and form no part of the claimed design.
